PORTABLE RADIO CABINET

Melvin H. Boldt, Glenview, Ill., assignor to Zenith Radio
Corporation, a corporation of Delaware

Filed May 29, 1961, Ser. No. 65,374

Term of patent 14 years

(Cl. D56—4)

*FIG. 1**FIG. 2**FIG. 3*FIG. 6

FIG. 4

FIG. 5

FIG. 7

FIGURE 1 is a front elevational view of my design for a portable radio cabinet as it appears with its handle in an upwardly extended carrying position;

FIGURE 2 is a side elevational view thereof;

FIGURE 3 is a top plan view thereof;

FIGURE 4 is a bottom view thereof, partially in section;

FIGURE 5 is a side elevational view, partially in section, of my design with its handle shown in a retracted position to facilitate insertion of the radio in a pocket or carrying case;

FIGURE 6 is a side elevational view thereof, partially in section, and with its handle in a downwardly and rearwardly extended position to serve as a support for the radio cabinet when it is placed on a horizontal surface;

FIGURE 7 is an enlarged perspective view of the upper portion of my design which illustrates in detail surface configurations of the speaker grille schematically shown in FIGURE 1.

The back of the portable radio cabinet is plain and unornamented.

The dominant features of my design reside in the portions of the drawing shown by means of full lines.

I claim:

The ornamental design for a portable radio cabinet, substantially as shown and described.
